DEVICE FOR MAKING SHOE LASTS BY PROFILE MILLING

Harald Werklund, Simrishamn, Sweden, assignor
to A B Svenska Skolästfabriken, Jarrestad,
Sweden

Application December 13, 1948, Serial No. 65,026
In Sweden December 18, 1947

3 Claims. (Cl. 142—15)

1

This invention relates to a device for optionally varying the heel and toe heights when profile milling shoe lasts in a so-called last-turning lathe and will be described more in detail in the following, reference being had to the accompanying drawings, in which

Fig. 1 shows a shoe last arranged in natural position on a horizontal plane.

Fig. 2 shows two uniform shoe lasts of different sizes in a similar manner.

Fig. 3 is a front view of a last-turning lathe provided with a device according to the invention.

Fig. 4 shows the same lathe, as seen from above.

Fig. 5 is an axial section of the embodiment of the invention, used in the lathe according to Figs. 3 and 4.

Fig. 6 shows a detail of an automatic control device, and Fig. 7 shows a cross-sectional view taken along line VII—VII in Fig. 5.

A usual shoe last consists, as seen from Fig. 1, of a toe portion 1, an instep portion 2 and a heel portion 3.

When the last is arranged in natural position on a horizontal plane 4, the underside of the heel portion 3 is at its rear at a certain height k over the plane 4. This height is called the heel height, because it corresponds to the necessary height of the heel of the shoe to be manufactured with the aid of the last. The front end of the under side of the toe portion is at a certain height over the plane 4, and this height is called the toe height. There is no certain relation between the heel and toe heights, but quite generally it may be said that for each heel height there is a certain toe height which is best suited for the appearance of the shoe model in question.

Shoe lasts are usually manufactured in a large series of sizes or numbers by profile milling in a so-called last-turning lathe, in which a model or template and one or more last blanks are rotatable about axes of rotation extending longitudinally of the model and the last blank or blanks, respectively. The model is manufactured by hand by a relatively well-paid last-modeller. The model is made in the so-called model size, which is generally the most usual size, i. e. for a man's last No. 42, for a lady's last No. 37. Bigger and smaller size numbers of the last form in question are made with the aid of the same model by enlargement or reduction during the profile milling operation by means of a pantograph mechanism.

Such an enlargement or reduction is disadvantageous owing to the fact that in this type of operation the last is executed uniformly with respect to the model using the identical dimensions

2

and relationships. Actually in this type of operation both the heel and toe heights vary in size relatively to the model, as appears from Fig. 2, in which on the one hand the model 5 is shown with its heel height k and toe height t and on the other hand a last 6 copies by profile milling and by enlargement from the model is shown and arranged on the same reference plane 7, so that it will readily be seen that in the enlarged last copy 6 the heel height has been increased with the distance k' , while the toe height has been increased with the distance t' .

To facilitate the manufacture of heels and to avoid re-adjustment of the machines that are used for mounting the heels, the shoe manufacturers want to have the same heel height for a certain number series of each shoe model. In a lady's shoe model with a heel height of e. g. 50 millimeters the manufacturer wants to have this heel height not only in the model number 37 but also in all other sizes from e. g. No. 34 up to No. 41. For a heel height of 50 millimeters the most suitable toe height is about 7 millimeters, and this toe height is therefore desired in all size numbers within the number series in question.

In order to meet these requirements it has been proposed that when profile milling shoe lasts in a last-turning lathe the model shall be swung relative to its axis of rotation in one or more stages of the milling of the last blank or blanks. This swinging movement may take place automatically and at a determined speed, but also half-automatically and at varying swinging speeds for obtaining the desired corrections. The automatic swinging should be used as a rule when producing whole number series of lasts, i. e. in the production of lasts, and the half-automatic swinging when producing new models having considerably diverging heel and toe heights.

The present invention relates to an improved device for automatically or half-automatically swinging the model in relation to its axis of rotation during the last turning operation. A preferred embodiment of the invention is shown by way of example in Figs. 3 to 6 of the accompanying drawings and will now be described in detail.

Referring to Figs. 3 and 4, the last-turning lathe is of a known construction comprising a frame 8, on which a headstock 9 and a tailstock 10 are mounted for clamping a last model 11. Moreover, a headstock 12 and a tailstock 13 for clamping two last blanks 14 and 15 are mounted on the frame 8. The spindles of the headstocks 9 and 12 are driven in a known manner by a

motor (not shown) enclosed in the frame 8 through a drive shaft 16. It should be observed that the two spindles of the headstock 12 are rotated in opposite directions for obtaining a right-foot last and a left-foot last. As appears from Figs. 3 and 4 the model 11 and the last blanks 14 and 15 are each clamped at the toe and the heel, so as to rotate about a longitudinal axis.

A tracer having the form of a roll 17, is mounted on a longitudinally reciprocating arm 18 disposed on a carriage 19 displaceable on the frame 8 in parallel with the axes of rotation of the model and the last blanks. An arm 20 is longitudinally movable on the carriage 19 and carries a milling cutter 21, corresponding to the tracer roll 17, for each of the last blanks 14, 15, the said arm 20 being mechanically coupled with the arm 18 by means of a pantograph mechanism so as to be reciprocated in a determined relation to the reciprocating movements of the arm 18. Furthermore the known pantograph mechanism is so constructed that the movements of the milling cutters 21 parallel to the axes of rotation of the last blanks are in a normally fixed, but alternatively adjustable relation to the movements of the tracer roll 17 parallel to the axis of rotation of the model 11. By suitable adjustment of the pantograph mechanism it is thus possible to mill the last blanks 14 and 15 bigger or smaller than the model 11, as desired.

To attain the above-mentioned relative swinging movement between the model 11 and the axis of rotation thereof during the profile milling operation there is used in the embodiment shown in Figs. 3 to 7 a mechanism which appears best from Figs. 5 and 7. On the spindle 22 of the headstock 9 there is fixed a body portion 23 forming a guide for a holder 24 for fixing the model 11. The holder 24 is guided by a curved guide groove in the body portion 23 having side and front members 25 and 25a, respectively, and a bottom wall 26 against which the end of the holder 24 is applied. The holder 24 is movable along the guide means 25, 25a and 26 approximately at right angles to the axis of rotation of the spindle 22, but the guide means are somewhat curved with their centre of curvature situated on the means 27 (Fig. 3) for fixing the end of the last model 11, supported by the tailstock 10, so that the model is safely clamped without any play when moving the holder 24. At each side of the holder 24 nuts 28 extend between the guide members 25a. The said nuts 28 are in engagement with a screw 29 extending freely through a hole 30 provided in the holder 24. At the ends of the guide means 25, 25a, 26 the screw 29 is journaled in bearings 31 on the body portion 23 so as to be rotatable but not displaceable. When rotating the screw 29 the holder 24 is displaced along the guide means 25, 25a, 26 by the nuts 28. The axis of rotation of the model coincides in the drawings with the center axis of the spindles 22 and 27 and in the embodiment shown it is always fixed in relation to the machine frame, whereas during the rotation the model itself can be pivoted about its point of suspension on the spindle 27 by moving the member 24 along the guide 25 so that the model occupies different angular positions in relation to its axis of rotation, i. e. the center axis of the spindles 22 and 27.

At its one end the screw 29 has a bevel gear 32 engaging with a bevel gear 33 attached to one end of a shaft 34 mounted in the body por-

tion 23 in parallel with and spaced from the axis of rotation of the body portion 23, determined by the spindle 22. The other end of the shaft 34 carries a planet gear 35 engaging with a sun gear 36 which is freely rotatably mounted on the body portion 23 coaxially with the axis of rotation thereof.

On the frame of the headstock 9 there is fixed a sleeve 37 surrounding the spindle 22 and the portion of the member 23 passed on to the spindle. The sleeve 37 has mounted thereon a brake means or a clutch disc 38 having coupling teeth 39 (or a frictional covering) for engagement with corresponding coupling teeth 40 (or a frictional covering) provided on the sun gear 36 freely rotatable on the body portion 23. The clutch disc 38 is non-rotatably but axially movably mounted on the sleeve 37 when the model 11 is to be automatically swung in relation to its axis of rotation, and is rotatable and axially movable on the sleeve 37, when the model 11 is to be half-automatically swung in relation to its axis of rotation by manual control of the disc 38.

Normally the clutch disc 38 is at a distance from the sun gear 36 which will therefore rotate together with the body portion 23 during the rotation of the body portion by means of the spindle 22, because the said gear is actuated by the planet gear 35. Thus, the screw 29 will thereby be at a standstill relatively to its bearings, so that the holder 24 is retained in adjusted position. However, if the clutch disc 38 is moved towards the sun gear 36, so that the coupling teeth 39 and 40 are engaged, the clutch disc, when held against rotation, will retain the sun gear 36 stationary relatively to the frame of the lathe, while the body portion 23 is rotated by the spindle 22. Thereby the planet gear 35 will roll against the sun gear 36, so that the bevel gears 32, 33 are rotated and in turn rotate the screw 29, whereby the holder 24 is moved along the guide means 25, 25a and 26. Thus, the model 11 is swung about the fixing means 27 of the tailstock 10, whereby a relative swinging movement is obtained between the model and its axis of rotation for the purpose aimed at.

The swinging of model 11 in relation to its axis of rotation should be effected during the milling of the instep portion of the last, and in the embodiment shown this swinging movement is effected automatically or by hand. The automatic swinging movement is realized by means of a control device comprising a rod 42 mounted below the model 11 in a bearing 41 (see Figs. 3 and 4) on the frame 8 of the lathe so as to be movable parallel to the axis of rotation of the spindle 22. The said rod 42 is connected by means of a transverse rod 43 (Fig. 4) in the frame 8 to the carriage 19, so that it is reciprocated together with the arm 18 and the tracer roll 17. A plate 44 (see also Fig. 6) extending upwards from the rod 42 is exchangeably attached to the end of said last-mentioned rod. In a certain position 65 of the rod 42 and thus of the tracer roll 17 the plate 44 comes into contact with a transverse arm 45 on a shaft 46 which is journaled in bearings 47 on the frame of the headstock 9. At its upper end the shaft 46 has two sidewardly extending arms 48 engaging in a groove 49 provided in the clutch disc 38 (see also Fig. 5). Between the bearings 47 a helical spring 50 is wound around the shaft. One end of said spring is fastened to the shaft 46 and the other end of the spring is fastened to the upper bearing 47 so

that the spring tends to hold the shaft 46 in such an angular position that the clutch disc 38 occupies a position distant from the gear 36. When, during the displacement of the rod 42 together with the tracer roll 17, the plate 44 contacts the arm 45 and continues its movement, the arm 45 is swung by the plate 44 so that, the shaft 46 is rotated in such a way that the arms 48 move the clutch disc 38 into engagement with the gear 36, the screw 29 displacing the holder 24 in the above manner. The arm 45 rides against the surface of the plate 44 during passage of the arm by the plate and after the plate 44 has passed the arm 45 completely the helical spring 50 returns the clutch disc 38 to its inactive position in which it is out of engagement with the gear 36, whereby the displacement of the holder 24 is stopped. The plate 44 is preferably attached to the rod 42 in such a position, that the displacement of the holder 24 takes place during milling of the instep portion of the last, and the plate 44 should be of such a length longitudinally of the rod 42 that the swinging, necessary for the last in question, of its axis of rotation 11 in relation to the model is obtained. Since this swinging movement must be different for different last numbers, the plate 44 has to be replaced by a plate of another length, when another last number is to be milled with the aid of the model 11. Sometimes it may be desirable to divide the necessary relative swinging movement between the model 11 and its axis of rotation into two steps that are taken during the milling of different portions of the last, and in doing so it is of course possible to arrange two plates 44 of suitable dimensions at desired points along the length of the rod 42.

Of course, the invention must not be considered as limited to the embodiment described above and shown in the drawings, for several modifications may be made without going outside the scope of the invention. It may be pointed out especially that it is possible to dispose a swinging device 23 to 50 both at the heel and the toe of the model 11, or the swinging device may be disposed at the toe instead of at the heel.

What I claim and desire to secure by Letters Patent is:

1. A device for supporting one end of a shoe last from a spindle in a last-turning lathe, comprising a body portion supported by said spindle, a sun gear mounted for rotation around the axis of said spindle on said body portion, a planet gear rotatably mounted on said body portion and meshing with said sun gear, a first bevel gear connected to said planet gear and rotatable thereby, a shaft rotatably mounted on said body portion and extending substantially at right angles to the axis of said spindle, a second bevel gear fixed to said shaft and meshing with said first bevel gear, guiding means on said body portion extending along said shaft, screw thread means on said shaft, a holder for said end of the shoe last, nut means on said shaft engaging said screw thread means, said guiding means partially surrounding and engaging said holder and said nut means to prevent rotation of said holder and nut means around the axis of said shaft, when said shaft is rotated, and guiding said holder and nut means along said shaft, when said nut means are screwed along said shaft during rotation of said shaft, and means mounted on the frame of the lathe and axially movable to engage said sun gear to prevent rotation thereof and to

cause a relative rotation of said sun gear in relation to said body portion, when said body portion is rotated together with the last, in order to cause rotation of said planet gear, said bevel gears and said shaft for shifting said holder and nut means along said shaft during the last turning operation.

2. A device for supporting one end of a shoe last from a first spindle in a last-turning lathe, 10 the other end of said last being pivotally connected to a second spindle in the lathe, comprising a body portion supported by said first spindle, a sun gear mounted for rotation around the axis of said first spindle on said body portion, a planet gear rotatably mounted on said body portion and meshing with said sun gear, a first bevel gear connected to said planet gear and rotatable thereby, a shaft rotatably mounted on said body portion and extending substantially at 20 right angles to the axis of said first spindle, a second bevel gear fixed to said shaft and meshing with said first bevel gear, guiding means on said body portion extending along said shaft, said guiding means being curved with the axis of curvature at right angles to said first spindle and substantially coinciding with the pivot axis for said other end of the last, screw thread means on said shaft, holder means for said one end of the last, nut means on said shaft engaging said 30 screw thread means on said shaft, said guiding means partially surrounding and engaging said holder means and nut means to prevent rotation of said holder means and nut means around the axis of said shaft, when said shaft is rotated, and guiding said holder means and nut means along said shaft, when said nut means are screwed along said shaft during rotation of said shaft, for swinging said one end of the last around the pivot axis for said other end of the last while, 40 due to the curvature of said guiding means, maintaining said holder means on a constant distance from said second spindle, and means mounted on the frame of the lathe and axially movable to engage said sun gear to prevent rotation thereof and to cause a relative rotation of said sun gear in relation to said body portion, when said body portion is rotated together with the last, in order to cause rotation of said planet gear, said bevel gears and said shaft for shifting said holder means and nut means along said shaft during the last turning operation.

3. A device for supporting one end of a shoe last from a spindle in a last-turning lathe, comprising a body portion supported by said spindle, 55 a sun gear mounted for rotation around the axis of said spindle on said body portion, a planet gear rotatably mounted on said body portion and meshing with said sun gear, a first bevel gear connected to said planet gear and rotatable thereby, a shaft rotatably mounted on said body portion and extending substantially at right angles to the axis of said spindle, a second bevel gear fixed to said shaft and meshing with said first bevel gear, guiding means on said body portion 60 extending along said shaft, screw thread means on said shaft, holder means for said end of the shoe last, nut means on said shaft engaging said screw thread means on said shaft, said guiding means partially surrounding and engaging said holder means and nut means to prevent rotation of said holder means and nut means around the axis of said shaft, when said shaft is rotated, and guiding said holder means and nut means along said shaft, when said nut means are screwed along said shaft during rotation of said 70 shaft.

4. A device for supporting one end of a shoe last from a spindle in a last-turning lathe, comprising a body portion supported by said spindle, a sun gear mounted for rotation around the axis of said spindle on said body portion, a planet gear rotatably mounted on said body portion and meshing with said sun gear, a first bevel gear connected to said planet gear and rotatable thereby, a shaft rotatably mounted on said body portion and extending substantially at right angles to the axis of said spindle, a second bevel gear fixed to said shaft and meshing with said first bevel gear, guiding means on said body portion 75 extending along said shaft, screw thread means on said shaft, holder means for said end of the shoe last, nut means on said shaft engaging said screw thread means on said shaft, said guiding means partially surrounding and engaging said holder means and nut means to prevent rotation of said holder means and nut means around the axis of said shaft, when said shaft is rotated, and guiding said holder means and nut means along said shaft, when said nut means are screwed along said shaft during rotation of said shaft.

shaft, and brake means mounted on the frame of the lathe and axially movable to engage said sun gear to lock it against rotation together with said body portion in order to cause rotation of said planet gear, said bevel gears and said shaft, for shifting said holder means and nut means along said shaft, when said body portion is rotated together with the last during the last turning operation.
